UNITED STATES PATENT OFFICE.

ALBERT MUNSEY, OF SWAMPSCOTT, MASSACHUSETTS, ASSIGNOR TO MUNSEY SHANK & COUNTER CO., OF LYNN, MASSACHUSETTS, A COPARTNERSHIP.

SHOE-SHANK.

No. 903,140.

Specification of Letters Patent.

Patented Nov. 3, 1908.

Application filed May 11, 1908. Serial No. 432,081.

To all whom it may concern:

Be it known that I, ALBERT MUNSEY, a citizen of the United States, and a resident of Swampscott, in the county of Essex and 5 State of Massachusetts, have invented an Improvement in Shoe-Shanks, of which the following description, in connection with the accompanying drawings, is a specification, like letters on the drawings representing like 10 parts.

This invention relates to shoe shanks, which while they may be of general application are particularly intended for use in connection with turn shoes.

15 In order that the principles of the invention may be readily understood, I have disclosed a single type or embodiment thereof in the accompanying drawings, wherein

Figure 1 is a vertical, longitudinal section 20 taken through a shoe to which my invention is applied; Fig. 2 is a bottom plan view of a portion of a turn shoe, with parts omitted, showing my invention applied thereto; Fig. 3 is a plan view of the under side of the shank; 25 and Fig. 4 is a vertical, transverse section upon the line 4—4, Fig. 1.

Referring more particularly to the drawing and to the particular type of the invention therein represented, the body of the shank is 30 indicated at 1, it being preferably and herein represented as composed of a single layer of some suitable material, leather board being preferably used. Heretofore it has been sought to impart proper curvature and 35 strength to a shoe shank by securing a longitudinally disposed spring thereto between the outer and the next adjacent layer thereof. Instead of applying a strengthening spring to the flush face of the shank, this being at- 40 tended by certain serious defects, I longitudinally recess or countersink the body of the shank as indicated at 2 and secure in said recess a plate spring 3 in any suitable manner, as, for example, by nails 4 at suitable points 45 and preferably short of the ends of the spring as indicated in Fig. 1.

It will be apparent that, as shown in Fig. 1, the body of the shank, which is recessed or countersunk in any suitable manner to receive the spring, is made of the proper or predetermined curvature and that the spring 3, which is secured in said recess by nails 4, is also of the proper or predetermined curvature, so as to fit therein and preferably flush 55 with the outer surface thereof. I am aware

that it has been sought to embed a rod of malleable metal in a shoe shank, but in such case there is no resiliency imparted to the shank by the stiffener. Moreover, the longitudinal recess or countersink 2 being of larger dimensions than the spring 3, as shown in Figs. 2 and 3, permits a slight degree of free play of the spring in the recess. Thus, in the event of unequal pressure on the sole of the shoe, occasioned by any twisting action thereof, or 60 in the event that the heel is unevenly worn, the result is neither to disrupt nor tear the spring from the shank, nor to break the spring, nor to injure the shank adjacent the edges of the ends of the spring, as would 65 be the result were the recess in the shank of the same dimensions as the spring, as must be the case were the spring to be forced by pressure to embed itself in the shank. Moreover, and as represented in 70 Figs. 2 and 3, the rearmost nail 4 is at a considerable distance from the rear end of the spring 3. This permits a very considerable 75 degree of free play of the rear end of the spring in the recess when the heel is unevenly 80 worn, and thus prevents the spring from being torn from the shank as would be the case if the rear nail 4 were at or near the rear end of the spring, and also prevents the lateral 85 edges of the spring from cutting into the shank.

By embedding the spring in a recessed or countersunk portion of the shank, many important advantages are secured. For example, the shank may be composed of a single piece without an overlying layer. A smoother finish may be given the shank, inasmuch as the spring preferably lies in said recess with its outer or under surface flush with the under surface of the body of the shank. By locating the spring in the recess, it is more securely held from lateral or longitudinal displacement and is thoroughly protected. Said spring being embedded, as it were, in the very substance of the shank, it is 90 substantially incorporated therewith and imparts its strength and resiliency thereto much more efficiently than though it were merely attached to a flush face thereof. Preferably the rear end of the spring 3 extends to the rear of the heel breast so as to 95 overlie the heel 5, which affords a firm pivotal or bearing point for the flexure of the spring in walking. Were the spring not seated in a recess, it could not be extended 100 110

over the heel without tipping the latter and thus seriously impairing the shoe.

In advance of the heel end of the shank, I preferably reinforce the same by providing a thickened arch supporting filler portion. While such thickened portion may be useful in various types of shoes and imparts a transversely rounded or convex shape to the shank of the shoe in whatever type it be employed, as indicated at 6 in Fig. 4, it is particularly useful in turn or welt shoes, inasmuch as it acts as a filler for the space between the seams. Owing to the non-existence of an inner sole in a turn shoe, it is desirable to fill the cavity thus resulting, and this I find to be most effectively accomplished in the manner stated. The thickened filler portion also serves an important function as an arch supporter. While in certain embodiments of my invention the protruding, thickened portion of the shank may be integral therewith, preferably an elongated strengthening filler patch 7 is secured to the shank in advance of the heel portion and along opposite edges of the recess, as by nails 8. While said patch may be of any desired extent, I preferably terminate it short of the rear or heel end of the spring 3. It is apparent that if desired the opposite end of the patch may terminate short of the adjacent end of the spring. If desired, one or both ends of the patch may be beveled, as indicated at 9, and a general rounded effect may be given thereto transversely.

Important advantages arise from the use of a filler patch underlying a countersunk spring. It is found in practice easier to apply the latter to a flush surface, and a better and smoother union of the patch and the body of the shank may be secured. The patch moreover aids to hold the spring in place and prevents it from working either up into or through the shank, or down into or through the sole 12. Furthermore the patch may be secured to the body of the shank immediately adjacent the edges of the spring. This is of importance, as the shank is usually very narrow at this point. It is apparent that the patch or enlargement gives additional strength to the shank and to the shoe as it reinforces the action of the shank and spring in supporting the foot as well as serving as an arch support, and giving the desired crowned or curved appearance to the sole 12 underlying the same.

In applying the shank to a turn shoe, the upper 10 may be secured to the shank as by nails 11, after which the sole 12 is secured to the rear portion of the upper and the heel 5 is then applied to the shoe. The spring 3 is a flat spring in that it has no abruptly bent portion, but it may be and preferably is longitudinally curved to conform to the curvature of the shank, if that be curved. The shank 1 is flat in the same sense.

Having thus described one type or embodiment of the invention, I desire it to be understood that although specific terms are employed, they are used in a generic and descriptive sense and not for purposes of limitation, the scope of the invention being set forth in the following claims:

1. A shoe shank having a longitudinally disposed recess in the outer face thereof, a plate spring located in said recess and substantially flush with the outer face of the shank, and an elongated, strengthening filler patch secured to the body of the shank and underlying the spring.

2. A shoe shank having a body composed of a single layer of material longitudinally recessed in its outer face, a plate spring located and secured in said recess and substantially flush with the said outer face of the body, and an elongated, strengthening, arch supporting filler patch secured to the said body along the side edges of said recess, but terminating short of the rear end of said spring.

3. As an article of manufacture, a shoe shank having a recess formed therein for the insertion of a stiffener, and of reduced thickness where recessed, a flat spring stiffener inserted in said recess and resting against the bottom thereof, and a filler patch applied to the recessed face of said shank.

4. As an article of manufacture, a shoe shank having a recess formed therein for the insertion of a stiffener, and of reduced thickness where recessed, a flat spring stiffener inserted in said recess and resting against the bottom thereof, and a filler patch applied to the recessed face of said shank, said filler patch having a beveled end or ends.

5. As an article of manufacture, a bevel edged shoe shank having a recess formed in the narrower face thereof, a flat, spring stiffener inserted in said recess, and a filler patch applied to said narrower face and within the limits thereof, and covering said stiffener and similarly beveled.

6. As an article of manufacture, a shoe shank having a recess formed therein for the insertion of a stiffener, and of reduced thickness where recessed, a flat spring stiffener inserted in said recess and resting against the bottom thereof, said stiffener being of smaller dimensions than said recess.

7. As an article of manufacture, a reinforced shoe shank of predetermined longitudinal curvature, comprising a shank body of predetermined longitudinal curvature and having a recess formed therein for the reception of a stiffener, a flat spring stiffener of similar and previously imparted longitudinal curvature inserted in the recessed part of said shank body, and a filler patch secured to the recessed face of said shank body.

8. As an article of manufacture, a flat shoe shank having a recess formed in its under face for the insertion of a stiffener and of

reduced thickness where recessed, a spring stiffener flat throughout, inserted in said recess and resting against the bottom thereof and means to secure said spring in said recess.

5 9. As an article of manufacture, a shoe shank having a recess in one face thereof, and a plate spring secured in said recess, the spring being secured in said recess in advance of the rear end thereof so as to leave the rear 10 end free for movement relative to the walls of said recess.

10 10. As an article of manufacture, a reinforced shoe shank of predetermined longitudinal curvature, having a recess formed in its 15 under face for the insertion of a stiffener and

of reduced thickness where recessed, and a spring stiffener flat throughout but of similar and previously imparted longitudinal curvature inserted in said recess and resting against the bottom thereof, and nails penetrating said spring and securing it in said recess. 20

In testimony whereof, I have signed my name to this specification, in the presence of two subscribing witnesses.

ALBERT MUNSEY.
